DRESSMAKER'S FOUNDATION AND GUIDE

Blanche Lavinia Howe, South Bend, Ind.

Application July 2, 1949, Serial No. 102,763

5 Claims. (CL. 223—68)

1

This invention relates to improvements in a dressmaker's foundation and guide.

In the making of dresses, coats and other garments, and especially in home dressmaking, considerable difficulty is experienced in making garments accurately by reason of the lack of a form which accurately corresponds or conforms with the contour or shape of the body of the person for whom the garment is being made. Dress forms or busts have been used for many years, built in standard sizes conforming generally to dress sizes, and the more elaborate of these forms have been provided with adjustments to permit a certain latitude of variation of size thereof. However, such adjustments are limited in number and it is not possible to compensate for abnormalities or departures from normal body contours as occur in many individuals due to posture peculiarities, growth peculiarities, or peculiarities resulting from injury or from surgery. Consequently, such standard forms are of little assistance to many individuals whose bodies depart from the normal for their size, due to one of the foregoing causes or to other causes.

A second type of dressmaking form has been developed which is molded to exact conformity with the shape of the body of the individual. Such forms can be used only by the individual for whom they are made, are quite expensive, and have a limited span of usefulness due to the occurrence of body changes with passage of time.

It is the primary object of this invention to provide a preformed device which may be donned by the user and accurately fitted to the body and then removed and applied over a conventional or standard type of dressmaker's form with padding applied between the same and the form as needed to secure in the assembled form a guide and three-dimensional replica corresponding with accuracy to the contours of the user's body and upon which the garment being made can be fitted with accuracy.

A further object is to provide a device of this character in which guides for all vertical and horizontal measurements to be taken in making a garment are provided accurately at the positions at which such measurements are to be taken.

A further object is to provide a device of this character which can be adapted to any figure or torso within a given size range quickly and easily and which can be altered rapidly to compensate for changes in body contours occurring with time or to compensate for the differences in the figures of different individuals of approximately the same size.

2

A further object is to provide a device of this character with arm-simulating portions adapted for detachable connection therewith.

In the drawing:

Fig. 1 is a view of the form in front elevation.
Fig. 2 is a view of the form in rear elevation.

Fig. 3 is a transverse sectional view taken on line 3—3 of Fig. 1, illustrating one of the horizontal measuring means applied.

Fig. 4 is a fragmentary top view, illustrating the manner in which the sleeve is mounted and also illustrating the manner in which padding may be applied between the guide and the standard form to which it is applied.

Referring to the drawing which illustrates the preferred embodiment of the invention, the numeral 10 designates a sheath or guide which is composed of a plurality of vertically elongated panels and is of proper shape to conform to the body of a user when fitted thereto. Each of the panels is preferably formed of cloth of stout or sturdy character, such as heavy muslin, broad-cloth, canvas or the like. The panels comprise two similar center front panels 12, two similar side front panels 14, two similar underarm side panels 16, two similar side back panels 18, and two similar center back panels 20. The panels 12, 14, 18, 20 are sewn together at their top edges to fit over the shoulders, and the panels 16 are of a width slightly less than sleeve width and extend below the armholes. The panels 14 and 18 are preferably shorter than the remaining panels and terminate slightly below hip level. The remaining panels 12, 16 and 20 preferably extend to floor length.

Each of the panels is preferably shaped to correspond generally to the shape of the portion of the body over which it fits. Thus the panels 12 and 20 taper inwardly from top and bottom toward the waist portion. Similarly, the remaining panels are shaped as required by their location.

Each of the panels is of a width greater than required to cover the portion of the body over which it fits so that, at any given cross-section of the unit 10, the total width of the constituent panels will be much greater than the girth of the body. The panels are secured together by sewing or basting along their longitudinal margins to provide a straight center front seam 22, a straight center rear seam 24, front seams 26 extending downwardly from approximately the centers of the shoulders, and rear seams 28 similarly extending downwardly from the centers of the shoulders. The seams 30 at the opposite edges of the underarm panels 16 preferably ex-

tend downwardly from the front and back of the sleeve or underarm portion. The seams 22-30 are formed inwardly spaced from the side edges of the constituent panels and the marginal portions 32 of the panels are folded inwardly, as best seen in Fig. 3. One of the two center seams 22, 24 is normally left open and is adapted to be secured by the use of pins, as illustrated at 34 in Fig. 2. The seams 22-30 preferably extend from the top or shoulder for the full length of the short panels, that is, for the full length of the panels 14 and 18. This is true of the center seams 22 and 24 connecting the center front panels 12 and the center back panels 20, as well as of the other seams at which a long panel is stitched to a short panel. The center panels 12 and 20 will preferably be contoured at their upper edges at 36 to provide a neck opening of a size fitting closely around the neck of the user, and the panels 14, 16 and 18 will be shaped at their upper portions to define arm-holes.

A plurality of tapes are stitched to the guide or sheath at selected vertical positions. Thus a tape 40 is stitched to one of the center front panels 12 at 42 adjacent the neck edge 36 and is adapted to be positioned as illustrated in dotted lines in Fig. 1 to extend around the base of the neck as a guide for collar measurement. A longer tape 44 is stitched to one of the front panels at 46 adjacent the front center seam 22 at approximately underarm or bust level and is of a length to pass completely around the bust as a guide for bust measurement, as shown in dotted lines in Fig. 1. A tape 48 is stitched at its center at 50 to one of the front panels 12 adjacent the seam 22 and is of a length to extend around and form a guide for measurement of the waist, as shown in dotted lines in Fig. 1. A tape 52 is stitched or secured at 54 to one of the front panels 12 adjacent the seam 22 and is positioned at hip level and is of a length to extend around the hips, as a guide for hip measurement as shown in Fig. 3. A tape 56 is stitched at 58 to one of the rear panels 20 at shoulder blade height and is of a length to extend across the back of a garment between the upper portions of the sleeves of a garment as a measurement guide, as shown in dotted lines in Fig. 2. Each of the underarm side panels 16 has a tape 60 stitched or secured thereto at a location just below the armhole, which tapes are of a length to pass around the upper part of the arm or over the shoulder as a guide for measurement of the sleeve to be formed. It will be understood that cords or straps or other suitable members may be used in place of tapes, if desired, and that each will be secured to the sheath at a limited portion thereof intermediate or spaced from its ends.

In the use of the device, assuming that all of the parts have been assembled as described but that one of the seams 22, 24, here shown as the rear seam 24, is open, the person to be fitted dons the guide reversed from normal position, that is, with the free marginal portions 32 of the panels positioned outermost. The open seam is then temporarily closed, as by the use of pins 34, and suitable markings are applied along the margins of the temporarily joined panels, for example, the rear central panels 20, to indicate the location at which the finishing seam is to be formed. Thereupon, such additional changes as may be required at the other seams between the various panels are made or marked.

Thus, if one shoulder is low, the shoulder seam at that side will be pinned to conform to the contour of the shoulder, or will be marked to indicate the point at which alteration is to be made. The same fitting or marking along the vertical seams to secure correspondence of the shape of the sheath with body contours throughout, can likewise be done. This may require opening of the seams at some points in order to enlarge the sheath at those points. In this way it is possible to fit the sheath very accurately to the figure or body of the wearer.

After removal of the sheath with the markings remaining thereon, the necessary changes in seams as marked are made. The sheath is then applied over a standard dressmaking form 62, shown fragmentarily in Fig. 4, which form may be of any desired size or character. The form 62 used will preferably be of a size slightly smaller than the dress size indicated for the user, so that the device or sheath 10 will fit thereon rather loosely. Thereupon padding 64, such as cloth, tissue paper or cotton wadding, may be inserted between the form 62 and the sheath 10, as illustrated in Fig. 4, to fill out the spaces at which the sheath 10 fits loosely upon the form 62. In this way the assembled form 62 and sheath 10 will conform exactly to the body contour of the person on whom the sheath 10 was fitted, and an exact replica of body contour will be provided upon which garments to be made may be fitted and draped, with assurance that the fit and drape will be the same when worn by the person as when draped upon the fitting device 10, 62.

The measurements of the various parts of the garment to be made can all be taken from the assembled device 10, 62. Thus all vertical measurements can be taken with accuracy along the seams 22-30, and all horizontal or transverse measurements can be obtained at the proper location by the use of the straps or tapes 44, 48, 52 and 56 as guides. The proper neck measurement can be secured from the tape 40 as a guide, and the proper sleeve seam measurement can be secured from the tapes 60 as guides. The measurements so secured can be transferred to the cloth and the various pieces thereof which are to be cut from a pattern, and a high degree of accuracy can thus be secured both in cutting and in sewing of the garment. The concluding work of finishing the garment can be performed in the usual manner with fittings easily made upon the fitting device 10, 62 from time to time as the work progresses and a check of the proper fit and drape is desired.

The device may be used for the making of coats and jackets and sleeved garments, as well as sleeveless garments or garments having only short sleeves, by the use of arm members 70. These arm members preferably comprise elongated padded members 72, made of stout and sturdy cloth similar to the material used for the body portion, and of substantially normal arm size and length and tapered at their upper ends to abut against and depend naturally from the form 62. The pad members 72 are encased in a sleeve sheath having an outer panel 74 and an inner panel 76 adapted to be joined together along a front seam 78 and a rear seam 80, one of which seams is sewed and the other of which is normally open. At its upper end the outer panel 74 preferably mounts two snap fastener parts 82 positioned forwardly and rearwardly of the longitudinal center of said panel, the panel preferably

having a downturned margin at which parts 82 are secured. The snap fastener parts are adapted to cooperate with and be detachably connected to complementary snap fastener parts 84 secured to the upper ends of the panels 14 and 18, respectively, as at downturned marginal portions of said panels. The snap fasteners 82, 84 are so arranged and positioned that, when connected, they will hold the sleeve sheath 74, 76 and the encased padded arm-simulating portion 72 in a natural free hanging position. Each sleeve sheath, of which one only is shown in the drawing, will have a plurality of measuring tapes, cords or straps secured thereto at different heights, such as the tapes 86, 88 and 90, each secured at an intermediate portion thereof at 15 92 to a sleeve panel, such as the panel 74. These tapes will preferably be positioned so as to provide guides for the measurement of the sleeve of the garment at armpit level, at elbow level and at wrist level, respectively.

The sleeve units 14, 76 may be donned and fitted to the arms of the user, marked for the location of the seam to be formed to complete the same, and then removed and the seam stitched. The sleeve sheaths 74, 76, when encircling the arm forms 72, and padded to fill out the sheaths, retain said arm forms. The snap fasteners 82, 84 or other detachable fasteners, such as hooks and eyes or mere straight pins, constitute the sole connection between the form 62 and the forms 72. The detachability afforded by fasteners 82, 84 permits the body portion of the garment to be made while the sleeve forms are removed, and also permits the garment sleeves to be made individually over the sleeve forms. Thus the sleeve forms may be connected to the body form only at such time as the fitting and sewing of the sleeve portions of the garment to the body portion is to be performed.

While the preferred embodiment of the invention has been illustrated and described herein, it will be understood that changes in the construction may be made within the scope of the appended claims without departing from the spirit of the invention.

I claim:

1. A dressmaker's guide comprising a plurality of narrow vertical elongated flexible cloth panels secured together along longitudinal marginal lines to provide a sheath adapted to fit around and conform accurately to the contour of the human body and having a neck opening and armholes, two of said marginal securing lines occurring respectively at the front and rear centers of said sheath, the upper ends of certain of said panels being secured together at the shoulder portion of the sheath and between each armhole and the neck opening, said panels each extending continuously from said shoulder portion 60 to a level below the hips of a wearer, said sheath

being open between two adjacent panels to facilitate donning and removal of the unit, means for releasably securing together the marginal portions of said last named adjacent panels, the panels and the longitudinal securing lines between panels at opposite sides of front and rear center lines being substantially symmetrical, said longitudinal securing lines being located to guide vertical body measurements with two longitudinal securing lines at the front extending from mid-points of the opposite shoulders and downwardly across the bust.

2. A dressmaker's guide as defined in claim 1, wherein some panels are longer than others.

3. A dressmaker's guide as defined in claim 1, and spaced flexible tapes each secured to said sheath at a part only of the tape and at a selected vertical position at which a horizontal measurement is to be taken.

20 4. A dressmaker's guide comprising a dressmaker's form, a cloth sheath having free vertical margins and adapted to be fitted accurately to the body of an individual and fitting detachably upon said form and having front and rear vertical center seams extending the full length of the sheath, means for releasably securing said free margins to close said sheath, elongated full length vertical measurement guides on said sheath spaced from said center seams and including guides extending from mid-point of the opposite shoulders downwardly across the bust, padding interposed between said sheath and form to fill out said sheath at parts fitting loosely on said form and a plurality of spaced flexible elongated tapes secured to said sheath at the exterior of the sheath for a portion only of their length, said tapes serving as guides for measurements and being of a length to encircle the sheath and form.

40 5. A dressmaker's guide as defined in claim 4, wherein said form simulates a torso, an arm-simulating form, a cloth arm sheath having free longitudinal margins, means detachably securing said arm sheath margins whereby said arm sheath is adapted to be fitted accurately to the arm of an individual and is adapted to fit detachably on said arm-simulating form, and means for detachably securing said arm form sheath to said first sheath.
